UNITED STATES PATENT OFFICE

THEODORE P. BROWN, OF WORCESTER, MASSACHUSETTS, ASSIGNOR TO SIMPLEX PIANO
PLAYER COMPANY, OF WORCESTER, MASSACHUSETTS, A CORPORATION OF MASSACHU-
SETTS.

PNEUMATICALLY-OPERATED MUSICAL INSTRUMENT.

No. 882,623.

Specification of Letters Patent. Patented March 24, 1908.

Application filed January 7, 1907. Serial No. 351,098.

To all whom it may concern:

Be it known that I, THEODORE P. BROWN, a citizen of the United States, residing at Worcester, in the county of Worcester and 5 State of Massachusetts, have invented a new and useful Pneumatically-Operated Musical Instrument, of which the following is a specification.

This invention relates to that class of musical instruments either self playing ones or 10 playing devices for ordinary instruments which are operated or controlled pneumatically.

The principal objects thereof are to provide for constructing the various parts in 15 such a way that they will be readily removable from each other and from the casing so that they may be cleaned or replaced individually and also to provide such construction that many of the parts may be made of 20 metal.

Further objects of the invention are to provide an improved form of primary and secondary valve boxes having means whereby 25 the diaphragms can be clamped in position without the employment of an adhesive thereby making these diaphragms readily removable, and providing for convenient and quick assemblage of the parts.

30 Another object of the invention is to provide readily removable couplings for the different pipes and tubes so as to assist in the ready dismantling or displacing of the several parts of the device; also to provide an 35 improved bleeding arrangement for the primaries and a permanently divided wind-chest.

Further objects and advantages of the invention will appear hereinafter.

40 For a disclosure of a device constructed in accordance with the principles of this invention, reference is to be had to the accompanying two sheets of drawings, in which

Figure 1 is an end elevation partly in section showing one embodiment of the invention. Fig. 2 is a plan of the same partly in section. Fig. 3 is a sectional view of one of the secondaries on the line 3—3 of Fig. 2.

Fig. 4 is a side elevation of one of the secondaries with the parts shown separated. Fig. 5 is a sectional view of one of the primaries on the line 5—5 of Fig. 2. Fig. 6 is a side elevation of the same, the parts being shown separated. Fig. 7 is a perspective view of

the bleeder-cartridge shown in Fig. 1, and 55 Fig. 8 is a plan of the permanently divided wind chest.

This invention is illustrated as being used with an instrument having a tracker-bar 10, each of the air channels 11 of which is connected by a tube 12 with an individual channel 13 in a channel box or the like 14. Each of these channels communicates through a tube 15 with a primary valve box 16. These valve boxes may be arranged in many ways, 60 65 and they are shown as arranged in sections of three. Each one is supported merely by a set of pipes 170 which constitute suction chambers for the primaries. Each of these primaries has an inlet 17 with which the corresponding tube 15 communicates, this inlet being shown in the form of a metal pipe section screwed into an opening in the bottom section 18 of the valve box. This section 18 has an upwardly extending flange 19 provided with an internal screw thread into 70 75 which a cap piece 20 is adapted to be screwed.

Between the seat inside the flange 19 and the bottom of the cap-piece, the edges of the 80 leather or other diaphragm 21 are placed, and the diaphragm is held in position by screwing the cap into the bottom section of the box. This construction provides for holding the diaphragm securely in position 85 without the use of adhesives so that in case of any trouble with the primary, the parts may be disassembled in a very easy manner, and the diaphragm removed, replaced or cleaned as may be desired. 90

It has been stated that the primary boxes are supported by the pipes 170 which constitute wind-chests therefor. These are shown as being arranged in three sections, but they can be arranged in any desired way, 95 and they communicate with a suction chamber at one end, or with one at each end as may be desired. It will be seen that these pipes open into a main chamber in each of the valve boxes above the diaphragm 21, so 100 that when the parts are in the position indicated in Figs. 1 and 5, the source of suction will communicate with a passage 22 through a tube 23 with which each of the valve boxes is provided. 105

When air is admitted through the passages 11, 12, 13, 15 and 17 to the underside of the diaphragm 21, the latter will conse-

quently rise and lift a valve 24 which will shut off the tube 23 from communication with the suction, and admit atmospheric air thereto. This tube is preferably in the form of a metal piping, and it communicates with a pipe section 25 which extends from one of the leaves of the corresponding operating pneumatic 26. The two pipe sections 23 and 25 are connected together by a flexible tube 27 which is preferably of rubber, so that the parts can readily be disconnected from each other. The pipe section 25 communicates through a passage 28 with the lower chamber 29 of the secondary valve box 30. The construction of this valve box is shown as very similar to that of the primary valve box.

The chamber 29 is formed by a bottom section similar to the bottom section 18, and 20 the diaphragm 31 is clamped into the same by means of an upper section 32. The diaphragm 31 operates a valve 33 to control the passage of air through an outlet pipe 34. The chamber in the upper section of this 25 valve-box above the diaphragm communicates through a pipe section 35 with a pipe section 36 which extends from a wind chest 37. Two pipe sections 35 and 36 are connected by rubber or other flexible tube 38, 30 so that the parts can be readily disassembled. Where the sections 35 and 36 are not in line, the tubes 38 are bent or curved as is shown at the upper and lower parts of Fig. 1.

In the interest of compactness a construction is provided in which the several pipes which are connected with each valve box are in the same plane. This can be done, in the primary valve box for example, by passing the pipes 170/ into the main 35 chamber in the upper box section 16, and passing the pipe 23 through this chamber into the inner chamber or passage 22. It will be seen however by reference to Fig. 2 that the upper chambers of both the primary 40 and secondary valve-boxes are shown as provided with horse-shoe shaped extensions. These are for the purpose of permitting the oppositely extending pipes 17 to communicate with this chamber, and to permit the 45 pipe 23 to extend through to the inner chamber in the valve box.

It will be noted that the secondary valve box is mounted by means of its lower section 50 29 in a removable manner on the outside of one leaf of the pneumatic 26, so that the parts thereof are readily accessible, and so that it can be removed or repaired without dismantling any of the portions of the pneumatic itself.

60 Each of the pipe sections 34 is connected with a pipe section 40 extending from the leaf of the pneumatic by means of a rubber tube 41 for a purpose similar to that described above. The pneumatics themselves 65 are mounted in a sort of metallic frame-work

of pieces 43 and 44 to which the fixed leaves of the pneumatics are screwed or otherwise removably secured in such a way that they can easily be dismounted. The movable leaves are connected with the action by removable metallic pieces 42. 70

The wind chests 37 are shown in the form of two separated parts, each consisting of a tube as shown in Fig. 8 having a closed end, and each communicating with a wind-supply 75 or storage device 45. One of these parts is connected with the bass pneumatics and the other with the treble pneumatics. As they are entirely separate from each other the bass and treble can be accented or modulated independently of each other. The pneumatics are shown as connected with the action in a well-known manner, and it will be understood that this connection does not constitute a part of this invention, and may be varied to suit any requirements. For the purpose of bleeding the primary pneumatics each of the passages 13 is connected by a pipe section 46 with a pipe section 47, all of which communicate with a single passage 48 which 80 may be located in the channel box 14 or elsewhere. This passage 48 has an outlet which is provided with a tube 49 connected with the bellows. 85

The pipe sections 46 and 47 are shown as 90 connected together by a readily removable flexible tube 50 which can readily be removed from both of the sections. In this tube is mounted a bleeder shell 51 having a pin-hole 52 as is well understood for bleeding purposes. 95 The objects of this construction are to provide for effectively bleeding all of the primary pneumatics, and at the same time to provide convenient means for keeping the passages clear. If any one of the shell pin-holes 52 is 100 found to be clogged up, the corresponding tube 50 can be removed and the shell readily cleaned out, or if all or a large number of them are stopped up, air can be forced through all of them from the tube 49 so as to remove 105 the obstructions from them. 110

It will be seen that provision is made for manufacturing the parts of the primary and secondary pneumatic valve boxes of metal, preferably cast metal, so as to simplify and 115 cheapen the construction, and at the same time to provide for locating these parts in such a way that they are all readily accessible and removable. Moreover by this construction, the diaphragms are not only removably mounted but the use of an adhesive which permanently fixes them in position is avoided. Moreover, the pipe sections are in most cases formed by metallic pipes which are joined at some convenient point by flexible rubber tubing which can be removed in a most simple and convenient manner to separate the parts. Moreover, the pneumatics are also removably mounted in position so that each one is individually remov- 120 125 130

able either with or without its corresponding valve boxes. The bleeding arrangement is similarly constructed, and can be cleaned in such a way that all the cartridges can be operated upon simultaneously, or each one can be attended to individually. Furthermore the wind-chests are permanently separated so that a different degree of tension can be secured in each one, whereby the treble and bass can be differently accented and modulated, and in general, the construction is greatly simplified and cheapened, and the parts rendered more accessible for repairs and replacements.

15 I am aware that many modifications may be made in the forms of the invention illustrated and described in the drawings, without departing from the spirit of the invention as expressed in the claims, and consequently 20 I do not wish to be limited to the particular form shown, but

What I do claim is:—

1. In a pneumatic musical instrument, the combination of an operating pneumatic, and 25 a secondary valve box removably mounted on one of the leaves thereof.

2. In a pneumatically controlled musical instrument, the combination of an operating pneumatic, a valve box mounted on the 30 outside thereof, and removable means for connecting the pneumatic with the valve box, whereby air may pass from one to the other.

3. In a musical instrument, the combination 35 of an operating pneumatic, a valve box mounted on one of the leaves thereof, and a connection between the valve box and the interior of the pneumatic, comprising a pipe section connected with the valve box, a pipe 40 section connected with the pneumatic, and a flexible tube connecting said pipe sections.

4. In a musical instrument, the combination 45 of an operating pneumatic, a valve box mounted on the outside of one of the leaves thereof, removable means for connecting the interior of the valve box with the interior of the pneumatic, said means being accessible from the outside of the pneumatic and valve box, a wind-chest, and removable means for 50 connecting the wind-chest with the valve-box.

5. In a musical instrument, the combination 55 with an operating pneumatic, of a valve box mounted on the outside of one of the leaves thereof, removable means for connecting a chamber of the valve box with the interior of the pneumatic, a pipe section extending from the interior of the valve box, a wind-chest having a pipe section extending 60 therefrom, and a flexible tube connecting said pipe sections.

6. In a musical instrument, the combination 65 of a series of valve boxes, a series of operating pneumatics connected therewith, a tubular wind-chest having pipe sections ex-

tending therefrom in different directions, and flexible removable tubes for connecting the pipe sections with said valve boxes.

7. In a musical instrument, the combination of a series of operating pneumatics, a 70 secondary valve box removably mounted on the leaf of each pneumatic and connected with the interior thereof, separate non-communicating pipes, each constituting a suction chamber, and means for removably connecting each of said pipes with certain of said valve-boxes.

8. In a musical instrument, the combination of operating pneumatics, valve boxes, a wind-chest consisting of two non-communicating 80 tubes placed end to end and independently supported, said tubes being connected with said pneumatics, said valve boxes being located in the connections between the tubes and pneumatics and a separate wind supply or storage device connected with each of said tubes.

9. A pneumatic musical instrument having a tubular main wind-chest, consisting of two non-communicating independently supported tubes placed end to end.

10. In a musical instrument, the combination of a wind chest consisting of two separate pipes, a plurality of secondary valve boxes connected with said pipes, an operating pneumatic for each of said valve boxes, said pneumatics, each having a passage therein communicating with the corresponding valve box, a pipe extending from said passage, and a primary valve box removably connected with said pipe.

11. In a musical instrument, the combination of a series of operating pneumatics with a corresponding series of metallic valve boxes removably mounted on said pneumatics and communicating with the interior thereof, each comprising a bottom section and a top section, one of said sections being adapted to be screwed into the other, said sections having meeting square surfaces, and a diaphragm held between said surfaces.

12. A pneumatic musical instrument having a plurality of metallic primary valve boxes, and suction pipes screwed into the walls of, and supporting, said boxes.

13. In a pneumatically controlled musical instrument, the combination with a tracker-bar and primary valve boxes, of a channel box having channels, each communicating with a passage in the tracker-bar of the instrument, and each communicating with a primary valve box, and a bleeder connected with each of said channels, said channel box having a channel communicating with all of said bleeders, said bleeders each comprising a removable tubular shell.

14. In a pneumatically controlled musical instrument, the combination with a tracker-bar and primary valve boxes, of a channel box having a channel for each of the tracker-

bar channels, and provided with a transverse channel, and a bleeder mechanism connected with each of said first named channels, all of the bleeder mechanisms communicating with the transverse channels and each comprising a tubular removable shell.

15. The combination with a channel box having a plurality of channels and a single additional channel, of a metallic pipe communicating with each of the first named channels, a series of metallic pipes communicating with the single channel, a flexible tube connecting each of the first named pipes with one of the second series of pipes, and a 15 bleeder in each of said flexible connections.

16. A bleeder device for a pneumatically controlled musical instrument having channels, a series of tubular bleeder shells, the end of each having a pin-hole, means for connecting each of said shells with one of said channels, and a channel with which all of said shells are connected.

In testimony whereof I have hereunto set my hand, in the presence of two subscribing witnesses.

THEODORE P. BROWN.
